UNITED STATES PATENT OFFICE

RICHARD JOHN HARRINGTON HUDSON, OF MUZAFFARPUR, INDIA

COLLAPSIBLE BOAT

Application filed June 21, 1928, Serial No. 287,246, and in Great Britain October 10, 1927.

This invention relates to collapsible boats of the kind having a keel and sides comprising two separate parts hinged together, one of said parts being hinged, in each case, to

5 said keel.

Such boats have previously been proposed but so far as I know have never been brought into use and the proposed constructions have not been such as to enable substantially large 10 boats of say 20 or 25 feet length to be constructed.

The present invention has for its object to provide an improved construction which will enable strong seaworthy boats to be constructed to serve as yachts' dinghies, ships' life-boats, and the like.

It is an object of the invention therefore to provide a collapsible boat having a keel and false stem and a false stern post movable 20 relatively thereto, the folding sides being hinged to said keel and to said false stem or stern post or both.

It is a further object of the invention to provide a boat having sides which are foldable about a bilge line in which the bottom 25 sides are hingedly connected to the keel and to a false stem and a false stern post, and the top sides are hingedly connected to said bottom sides.

30 It is a further object of the invention to provide in conjunction with the keel a stem and stern post rigidly secured thereto and a flexible false stem and a flexible false stern post movable relatively thereto and adapted 35 to be rigidly held in one or more predetermined positions.

It is a further object of the invention to provide a collapsible boat having hinged joints protected by canvas or other fabric, 40 means being provided whereby the said fabric is completely covered when the boat is in the erect position and is caused to be extended without folds within the joint to prevent chafing or wear.

45 It is a further object of the invention to

provide a collapsible boat in which the folding sides are adapted to flex during the folding movement, the sides being provided with stiffening battens lying along lines which remain straight during the flexing movement.

50

These and other objects of the invention will be made clear from the following description and set forth in the appended claims.

The invention is illustrated in one form of execution in the accompanying drawings 55 which show a ship's dinghy, but it is to be understood that this is by way of example only, and that the invention can be readily applied to lifeboats or any other form of boat usually requiring to be readily transportable, 60 and at the same time to be suitably strong during use.

In the accompanying drawings, Fig. 1 illustrates a central sectional view of the dinghy, Fig. 2 being a plan. Fig. 3 is a transverse section to Fig. 1, the boat being hitherto illustrated in the erected or opened position. Fig. 4 is a transverse section similar to Fig. 3 when the boat is collapsed, and Figs. 5 and 6 show on an enlarged scale one of the joints.

70

Turning now to the drawings, the form here illustrated comprises a strong keel 1, stem 2 and stern post 3, of rigid solid construction. The sides of the boat comprise top sides 4 and bottom sides 5 hinged together by a series 75 of hinges 6 running along the bilge line 7, the bilge line being indicated in broken lines in Fig. 1 where the joint between the sides is not plainly visible. The sides 4, 5 are formed of flexible solid material such as thin planking, or ply wood such as is already known in connection with the construction of boats, or steel plate, and the bottom sides 5 are hinged to the keel 1 by a series of hinges

80

8 lying along straight lines throughout the length of the keel. Forwardly and aft of the keel, however, they are hinged by continuous series of small hinges 9, 10 to a false stem 11 and a false stern post 12 which in the form shown are mounted on or comprise 85 90

flexible plates 13, 14 carried under the shoulders of the keel and held down by separate keel plates 15, 16. The false stern post 12 is adapted to be drawn up solidly against the stern post 3 by means of a screw 20 engaging in a bracket 21 attached to the false stern post and the false stem may be arranged to be similarly drawn up. With small boats, however, it may be found sufficient to have a single screw 20 at the stern as owing to the curvature of the bilge line joint and the resilience of the sides, the false stem and false stern post must move together. In this case, a toggle stirrup 50 may be employed at the bow.

In collapsing the boat from the position illustrated in Figs. 1, 2 and 3 the stirrup 50 is released and the screw 20 is rotated to allow or cause the false stern post 12 to move away from the stern post 3 which it naturally does under the resilience of the plate 14 and of the sides. The false stern post thereupon moves out aft to the position indicated in broken lines in Fig. 1. At the same time the top sides 4 fall, or are folded, inwardly in Fig. 3 about the hinges 6 and the false stem under the movement of the sides moves forwardly to the position shown in broken lines in Fig. 1. The bottom sides 5 tend to fold upwardly about the hinges 8 as the false stern post is moved outwardly and by easing by hand the movement of the sides 4, 5 simultaneously with the actuation of the screw 20, the boat can readily be collapsed into the flat position shown in Fig. 4.

In the form shown the bottom sides 5 are strengthened by battens or stiffeners 30 formed with enlarged heads to which the plates of the hinges 6 are attached. The battens or stiffeners in the case of the boat illustrated, which, as previously stated, has the shape of an ordinary dinghy, are set generally in the form shown and lie over portions of the sides which remain straight lines in the collapsed and open positions of the boat.

An examination of the drawing will show that the bottom side 5 tends to be twisted round the point of its attachment to the front of the keel in its forward half and to be curved more or less cylindrically about a line running athwart the boat in its after part, there being an unstrained or neutral zone A running obliquely in Fig. 2 between the ends of the two sets of battens.

In the case of a lifeboat, however, where the stem and stern are similarly shaped the strain in the sides would take a different form, and the battens 30 would be generally similar in arrangement in the fore and after parts of the boat, and would radiate from points near the foremost and aftermost ends of the keel.

It is to be understood of course that the top sides 4 and bottom sides 5 although curved considerably in the erect position as shown in Figs. 1 to 3, become practically plane in the collapsed position, as clearly indicated in Fig. 4, and the curve of the bilge joint 7 is designed so that the movement of the sides from the erect to the collapsed positions involves a steady straightening of the sides and can be effected without severe stress or over strain either of the sides or hinges at any part. In the erect position the sides are further stiffened at midships by stretchers 31 which may be hinged to the keel at 32 and may carry canvas bands 33 attached to their outer ends and adapted to form seats when the stretchers are extended. Floor boards 34 are hinged to the upper part of the keel and lie upon the bottom sides 5 as shown in Fig. 3 when the boat is erect; when the boat is collapsed they are rocked to a vertical central position and lie between the top sides 4 as shown in Fig. 4.

An important feature of the construction consists in covering all the joints with canvas on their outer sides and in protecting the said canvas of the boat against chafing or other damage when the boat is erect and in use.

In Figs. 3 and 4 the thick lines 36 indicate canvas coverings for the hinges 8, the edges of the canvas being engaged behind battens 37 attached to the keel and fender boards 38 attached to the bottom sides, the latter coming into close contact with the battens 37 when the boat is erect as clearly shown in Fig. 3 in order to protect the canvas from accidental damage. In the bilge line joints a similar canvas covering 40 is provided which is held between fender boards 41 and 42, Figs. 5 and 6, the board 42 having a bead or projection 43 adapted to fill the space between the ends of the boards 4, 5, to deflect the canvas into the curve shown in Fig. 3 so as to prevent it from folding or rubbing or from being caught in the hinge the fender boards 41, 43 being formed with complementary engaging faces to close the joint giving access to the canvas 40 as clearly shown in Fig. 5. Thus the attached sides of the fabric are so to speak, let in the wooden structure so as to be normally protected when the boat is in use.

In the forms shown the false stem 11 is held rigidly against the stem 2 in the open position by means of a toggle stirrup 50 engaging over a pair of hooks 51 attached to the false stem; and hinged cover plates 52 forming a fore-deck are folded over the bow. A usual fitting 53 and footstep 54 for a mast are provided, and a centre board 55 may be let in the centre of the keel. The rudder may be attached to bearings 56, 57, the bearing 56 being rigid with the stem 3 and the bearing 57 being attachable to the false stern post.

An engine may be arranged to be detachably carried in which case the propeller shaft may be permanently mounted in the keel in a suitable watertight bearing at its after end.

Obviously the invention is not limited to the precise form of construction illustrated, many details of which will be subject to variation at the discretion of the boat builder in accordance with the size, shape and strength 10 of the boat to which the invention is applied.

I claim:—

1. In a collapsible boat, a hinged joint, a fabric strip externally covering said hinged joint, a fender board covering said fabric strip 15 on one jointed member, a fender board covering said fabric strip on the other jointed member, one of said fender boards having a bead or protuberance to engage said fabric strip when the boat is in the erect position 20 to cause it to lie extended without folds within the joint.

2. In a collapsible boat, a keel, a flexible stem jointed thereto, a pair of bottom sides hinged to said keel and to said stem, a pair of 25 top sides hinged to said bottom sides and extending into juxtaposition with said stem, and a pair of cover plates jointed together and to said topsides to serve as a collapsible fore deck.

3. In a collapsible boat, a keel, a flexible 30 false stem, a flexible false stern post, folding sides hinged to said keel and said posts, said sides being adapted to flex during folding.

4. In a collapsible boat, a keel, a flexible 35 false stem, a flexible false stern post, folding sides hinged to said keel and said posts, said sides being adapted to flex during folding and having stiffening battens lying along 40 lines which remain straight during the flexing movement.

5. In a collapsible boat, a keel, a pair of 45 bottom sides hinged to said keel, a pair of top sides hinged to said bottom sides, said bottom sides overhanging said keel and being 50 jointedly connected together, said topsides being foldable inwardly of said bottom sides, and said folded sides being thereafter movable inwardly together to lie vertically of 55 said keel.

6. In a collapsible boat, a keel, a pair of 55 bottom sides jointed to said keel and having overhanging parts connected to each other for flexing movement, a pair of topsides hinged to said bottom sides along bilge lines, the joints between said pairs of bottom sides and between said bottom sides and topsides 60 extending to meet each other.

7. A collapsible boat having a keel and 65 foldable sides of solid material hinged thereto, said sides being foldable along a joint intermediate their height and being 70 flexible to allow the necessary extension of overall length to permit straightening during 75 folding.

8. In a collapsible boat, a movable false stem, a movable false stern post, folding sides hingedly connected to said false stem and stern post, said foldable sides comprising two 70 separate parts hingedly joined together, with one of said parts hingedly connected to said keel, and means to lock the stem and stern post in predetermined positions.

In testimony whereof I affix my signature.
